GARMENT

Sylvanus O. Jacks, San Francisco, Calif.

Application January 15, 1941, Serial No. 374,485

1 Claim. (Cl. 24—202)

This invention relates to improvements in garments and has particular reference to a shirt band or collar band.

The principal object of this invention is to provide means whereby the portion of the garment surrounding the neck may be adjusted, whether it be an attached or a detached collar, so that the wearer may have the greatest comfort possible without being limited to the exact size of the shirt.

A further object of the invention is to provide a device of this character which, in all intents and purposes, will have the appearance of an ordinary shirt and will conform to the standard practices.

A further object of the invention is to provide means for producing my invention in an economical manner.

Other objects and advantages will be apparent during the course of the following description.

In the accompanying drawing forming a part of this specification and in which like numerals are employed to designate like parts throughout the same,

Fig. 1 is a fragmentary front elevation of a shirt having my invention applied thereto;

Fig. 2 is an enlarged fragmentary view of an elongated buttonhole and the dividing element;

Fig. 3 is a fragmentary view of a collar constructed in accordance with my invention; and

Figs. 4 and 5 are diagrammatic illustrations of the manner in which the two overlapping parts may be adjusted relative to each other.

The ordinary shirt is provided with a neck band of a definite size so that when the same is buttoned around the neck, a fixed opening for the neck results. These shirts may be purchased too large or too small, and as a consequent the neck opening may be uncomfortable for the wearer if too small and unsightly if too large. Also, it is a well-known fact that these shirts often shrink in laundering. Furthermore, it may be possible that the wearer desires to loosen the neck band during a hot spell and yet cannot do so without presenting an unsightly appearance.

Applicant has, therefore, devised a means for adjusting the neck band of the shirt or the size of a detachable collar in such a manner that either of these devices may be readily adjusted to the wearer's neck or to his comfort and yet having the devices present a pleasing appearance.

My invention may be accomplished in several

ways and consists in arranging in horizontal alignment a plurality of closely arranged openings through which the collar button or fastening element may be placed.

5 In the accompanying drawing wherein for the purpose of illustration is shown a preferred embodiment of my invention, it will be noted in Fig. 3 I have shown the overlapping ends 5 and 6 of a collar 7, which overlapping ends are provided with elongated buttonholes 8 and 9, respectively. These buttonholes are divided into openings 11, 12, 13, and 14 by cross divisions 16.

In the preferred form shown in Fig. 2, the buttonhole 17 is divided lengthwise by a dividing element which consists of a wire so bent as to form crosspieces 18 extending across the buttonhole and dividing it into sections, one of which is occupied by the button 19 of this figure.

The goods forming the buttonhole will slide on 20 the crosspieces 18 sufficiently to permit the head of the button to pass between the edges of the buttonhole and and to then rest against one of the crosspieces.

It is obvious that when the two parts of the 25 collar or neck band are overlapped, as shown in Fig. 4, the button will pass through the openings, designated by the line A; and when the parts are overlapped, as shown in Fig. 5, the button will pass through the openings, designated 30 by the line B. Thus, the neck band or collar may be adjusted so as to produce a variation of several sizes for the accommodation and comfort of the wearer.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

An adjustable fastening means for the overlapping ends of a neck encircling garment and comprising elongated buttonhole openings formed in 45 each of said overlapping ends, and a dividing element embedded in each of said overlapping ends and having portions thereof extending across the buttonholes and serving slidably to divide the buttonholes into a plurality of independent 50 openings.

SYLVANUS O. JACKS.
